CLAIM

The ornamental design for a wedge clamp for panels or the like, as shown and described.

DESCRIPTION

FIG. 1 is a perspective view of a wedge clamp for panels or the like showing our new design; the portions of two panels being shown in broken lines for illustrative purposes only;

FIG. 2 is a side view taken from the right of FIG. 1; the side opposite being a mirror image thereof;

FIG. 3 is a front view thereof;

FIG. 4 is a rear view thereof; and,

FIG. 5 is a top view thereof, the bottom being a mirror image.
